UNITED STATES PATENT OFFICE.

MAY F. GARDNER, OF PITTSBURGH, PENNSYLVANIA.

PENHOLDER.

1,028,704.

Specification of Letters Patent. Patented June 4, 1912.

Application filed November 25, 1911. Serial No. 662,498.

To all whom it may concern:

Be it known that I, MAY F. GARDNER, a citizen of the United States of America, residing at Pittsburgh, in the county of Allegheny and State of Pennsylvania, have invented certain new and useful Improvements in Penholders, of which the following is a specification, reference being had therein to the accompanying drawing.

10 This invention relates to pen holders, and the primary object of my invention is to provide a compartment adapted to contain an eradicator or other erasing fluid.

Another object of this invention is to provide a pen holder with a compartment for an eradicator and to furnish the pen holder with novel means whereby a controllable quantity of the eradicator can be removed from the holder for erasure purposes.

20 A further object of this invention is to accomplish the above results by a mechanical construction that is durable, inexpensive to manufacture and highly efficient for the purposes for which it is intended.

25 With the above and other objects in view, the invention resides in the novel construction, combination and arrangement of parts to be hereinafter specifically described and then claimed.

30 Reference will now be had to the drawing, wherein:

Figure 1 is a side elevation of a pen holder in accordance with this invention, Fig. 2 is a similar view, partly broken away and partly in section, Fig. 3 is a side elevation of a detached cap, and Fig. 4 is an enlarged detail sectional view of the same, Fig. 5 is a horizontal sectional view taken on the line V—V of Fig. 4.

40 The reference numeral 1 denotes a pen holder, preferably made of glass or other vitreous material. The outer end of the holder is rounded, as at 2 and provided with a longitudinal opening 3, said opening being in communication with a compartment 4 that is adapted to contain an eradicator or an ink erasing fluid. In the opening 3 there is arranged a resilient bushing 5.

45 Detachably mounted upon the rounded end 2 of the holder 1 is a cap 6 made of glass

or a vitreous material. This cap has a socket 7 to receive the rounded end of the holder 1, said cap being retained thereon by friction. The outer end of the cap 6 has a funnel-shaped opening 8 in communication with a tubular stem 9 that is arranged longitudinally of the socket 7 and extends below said socket. The tubular stem 9 extends through the bushing 5 into the compartment 4. The bushing 5 is employed to prevent the stem from being broken while the pen holder is in use.

The outer end of the cap 6 has an annular bead or rim 10 and mounted upon said rim is the inner annular edge 11 of a compressible bulb 12, said bulb being in the form of an inverted cup. The bulb is made of leather or other flexible material and is employed for withdrawing a quantity of the eradicator from the compartment 4 of the pen holder 1.

By compressing the bulb 12 and then allowing the same to expand, a quantity of the eradicator or erasing fluid can be removed from the compartment 4. With a quantity of the eradicator within the tubular stem 9, the stem can be manipulated with the cap 6 serving as a handle, whereby ink can be readily removed from paper. The flow of eradicator is controlled by the pressure upon the bulb 12 and the quantity of eradicator that is not used can be easily returned to the compartment 4 by simply placing the cap 6 upon the rounded end of the holder 1.

85 The pen holder has been especially designed for bookkeepers and writers having use for eradicators and by using a pen holder in accordance with this invention, the necessity of having separate receptacles for eradicators or ink erasing fluids is obviated.

90 While in the drawing there is illustrated a preferred embodiment of this invention, I would have it understood that the structural elements are susceptible to such variations as fall within the scope of the appended claim.

What I claim is:

A pen holder having the outer end thereof

provided with an opening and an eradicator compartment, a resilient bushing arranged in the opening of said pen holder, a cap detachably mounted upon the end thereof and provided with a tubular stem extending through said bushing into said compartment, and a compressible bulb connected to said cap for drawing controllable quantities

of liquid from said compartment into the stem of said cap.

In testimony whereof I affix my signature in the presence of two witnesses.

MAY F. GARDNER.

Witnesses:

W. R. GARDNER,
MAX H. SROLOVITZ.
